SHEET COLLECTING AND FOLDING MECH-
ANISM FOR PRINTING PRESSESHoward M. Barber, Pawcatuck, Conn., assignor to
C. B. Cottrell & Sons Company, Westerly, R. I.,
a corporation of Delaware

Application March 1, 1937, Serial No. 128,332

5 Claims. (Cl. 270—47)

The object of this invention is to provide novel means whereby selected products of a different number of pages and page widths may be delivered in one direction or in opposite directions, as desired.

The object of this invention is more particularly to provide a novel means whereby the product of a web printing press, when the product is cut into an odd number of sheets or superimposed sheets, may be collected in full or in part on a collecting and folding cylinder having an even number of collecting surfaces, folded off therefrom, and delivered to one delivery in four page signatures or multiples thereof; the remaining sheet or sheets, if any, being folded off from the cutting and folding cylinder and delivered to another delivery.

A further object of my invention is to simplify the mechanism shown, described and claimed in my United States Letters Patent No. 1,968,630, dated July 31, 1934.

A practical embodiment of my invention is represented in the accompanying drawings, in which

Fig. 1 represents a diagrammatic side elevation showing one of the couples of a rotary web perfecting printing press in connection with which my improved sheet collecting and folding mechanism is used;

Fig. 2 represents a diagrammatic side elevation of my improved sheet collecting and folding mechanism;

Fig. 3 represents a detail view in side elevation illustrating the cams for controlling the sheet engaging and folding devices on the several cylinders;

Fig. 4 represents a similar view illustrating another form of cam used for silencing one of the collecting and folding cylinder cams and for silencing the sheet taking devices on the transfer and folding cylinder; and

Fig. 5 represents a detail section of the form of rotary cam illustrated in Fig. 3.

In the embodiment herein shown, the web is designed to be printed and perfected in a single color on each cycle of the press, forty-eight pages; six pages around and four pages across. In Fig. 1, one of the printing couples is shown, the form or printing cylinder being denoted by A and the impression by A'.

The printed web four pages wide may be fed from the press to the coacting web feed rolls 1 and 2 around the rolls B and F. Two narrow webs two pages wide may be fed from the press to the feed rolls 1 and 2 around the rolls B, C

and F. Four narrow webs one page wide may be fed from the press to the feed rolls 1 and 2 around the rolls B, C, F, D, E and G respectively. The feed rolls 1 and 2 advance the web or webs between the rotary cutter 3, in the present instance a cutting cylinder and the cutting and folding cylinder 4, to cut the web or webs into an odd number of sheets or superimposed sheets each cycle of the press. The rotary cutter 3 is provided with two equally spaced cutting blades 5 and 6 and the cutting and folding cylinder 4 is provided with three cutting slots 7, 8 and 9 for successive coaction with the cutting blades 5 and 6 of the said rotary cutter 3. The rotary cutter 3 is two-thirds the circumference of the printing cylinder A, or four pages around. The cutting and folding cylinder 4 has the same circumferential length as the printing cylinder A.

This cutting and folding cylinder 4 is provided with three sets of equally spaced sheet taking devices, in the present instance impaling pins 10, 11 and 12 and a folding blade 13. This folding blade 13 is arranged to coat, when desired, with a folding jaw 14 on a folding and delivery cylinder 15, which has the same circumferential length as the cutting and folding cylinder 4.

The collecting and folding cylinder 16 which has the same circumferential length as the rotary cutter 3 is provided with two equally spaced sheet engaging devices, in the present instance impaling pins 17 and 18, as well as two intermediate equally spaced folding blades 19 and 20, which folding blades coat at the proper times, when so desired, with a single set of folding jaws 21 on the folding and delivery cylinder 22, the circumferential length of which is equal to the printing cylinder A of the press.

A suitable packer delivery 23 is provided for receiving the signatures from the folding and delivery cylinder 15, and another oppositely arranged packer delivery 24 is provided for receiving the signatures from the folding and delivery cylinder 22.

The means which I have shown for controlling the operation of the several sheet engaging and folding devices for collecting, folding and delivering the selected product to one or both deliveries may be constructed, arranged and operated as follows:

A changeable rotary box cam is mounted on the shaft 25 of the cutting and folding cylinder 4, which box cam comprises a common half member 26 and two interchangeable half members 27 and 28. The common half member 26 has a semicircular cam groove 29 concentric with the

shaft 25. The interchangeable half member 27 has a semicircular groove 30 matching with the groove 29 and having an offset portion 31. The interchangeable half member 28 is provided with 5 a semicircular groove 32 matching with the groove 29 in the common half member 26. This groove 32 is concentric with the shaft 25.

When it is desired to control the action of sets of normally projecting impaling pins 17 and 10 18 on the collecting and folding cylinder 16 at their sheet taking point the rotary cam members 15 26 and 27 are used. A movable cam 33 is brought into and out of its position to engage the rollers 34, 35 of the sets of disappearing impaling pins 17 and 18 by providing the movable cam 33 with 10 a stud or roller 36 which travels in the cam groove 29, 30, 31. When it is not desired to control the action of the sets of disappearing impaling pins 17 and 18 at their sheet taking point 20 the cam members 26 and 28 are used and the cam 33 is thereby held out of its operative position as its stud or roller travels in the concentric cam groove 29, 32. A movable cam 37 controls the sets of disappearing impaling pins 17 25 and 18 on the collecting and folding cylinder 16 to permit the signatures to be folded off onto the folding and delivery cylinder 22. This movable cam 37 is provided with a stud or roller 38 which travels in the groove 39 of a rotary box 30 cam 40 mounted on the shaft 41 of the said cylinder 22, said groove 39 having an offset portion 42.

A stationary cam 43 is arranged in position to engage the stud or roller 44 of the folding jaws 35 21 on the folding and delivery cylinder 22 to open the jaws to receive the signatures from the collecting and folding cylinder 16. Another stationary cam 45 is arranged in position to engage the stud or roller 44 of the folding jaws 21 40 to open the jaws at the proper point to deliver the signatures to the delivery 24.

A changeable rotary box cam is mounted on the shaft 46 of the folding and delivery cylinder 15, which box cam comprises a common half member 47 and two interchangeable half members 48 and 49. The common half member 47 has a semicircular cam groove 50 concentric with the shaft 46. The interchangeable half member 48 has a semicircular groove 51 matching with the groove 50 and having an offset portion 52. The interchangeable half member 49 is provided with a semicircular groove 53 matching with the groove 50 in the common half member 47 and concentric with the shaft 46. When it is desired 55 to control the action of the sets of normally projecting impaling pins 10, 11 and 12 on the cutting and folding cylinder 4 at their sheet transfer point, the rotary cam members 47 and 48 are used. When it is not desired to control the action of the said sets of impaling pins 10, 11 and 12 at their transfer point the cam members 47 60 and 49 are used. The movable cam for controlling the action of these disappearing impaling pins 10, 11 and 12 is denoted by 54, which movable cam is provided with a stud or roller 55 traveling either in the cam groove 50, 51, 52 or the cam groove 50, 53, as the case may be. This movable cam 54 is arranged, when operating, to successively engage the studs or rollers 56, 57 70 and 58 on the impaling pins 10, 11 and 12 respectively.

A fixed cam 59 is arranged in position to open the jaws 14 on the folding and delivery cylinder 15 to coact with the folding blade 13 of the cutting and folding cylinder 4, said cam 59 engaging

the stud or roller 60 of said folding jaws. Another fixed cam 61 is arranged to engage the said stud or roller 60 to open the jaws to deliver the signatures to the packer delivery 23.

A laterally movable cam 62 of well known or 5 approved form is arranged to be brought into and out of the path of the studs or rollers 56, 57, 58 to withdraw the three impaling pins 10, 11 and 12 to transfer the entire product to the collecting and folding cylinder 16 or to withdraw 10 a selected two of these pins when one-third of the product is to be transferred to the folding and delivery cylinder 15.

In the embodiment of the invention shown and described herein the operation is as follows: 15

The full forty-eight page product of the press is collected, folded and delivered in any of the following combinations, to wit:

Four eight page signatures to delivery 24 and four four page signatures to delivery 23; or four 20 twelve page signatures to delivery 24; or two sixteen page signatures to delivery 24 and two eight page signatures to delivery 23; or two二十四 page signatures to delivery 24; or one thirty-two page signature to delivery 24 and one sixteen 25 page signature to delivery 23.

When the full web four pages wide is to be collected, folded and delivered, the web is cut into three sheets each cycle of the press. When the web is slit into two narrow webs two pages 30 wide the two webs are combined and then cut into three pairs of sheets each cycle of the press. When the web is slit into four narrow webs one page wide the four narrow webs are combined and cut into three groups of four sheets each, 35 each cycle of the press.

When four eight page signatures are to be delivered to the delivery 24 and four four page signatures to the delivery 23, the web four pages wide is fed between the rotary cutter 3 and the 40 cutting and folding cylinder 4. The cams 33 and 62 are operated so that the first and third signatures are taken by the impaling pins 17 on the collecting and folding cylinder 16. The two superimposed signatures on the cylinder 16 are 45 folded off onto the folding and delivery cylinder 22 and they are slit longitudinally by the slitters 63 into four eight page signatures and then deposited onto the delivery 24. The second signature is folded off from the cylinder 4 onto the 50 folding and delivery cylinder 15 and there slit longitudinally by the slitters 64 into four four page signatures and then deposited onto the delivery 23.

Where four twelve page signatures are to be 55 delivered to the delivery 24 the web four pages wide is cut on the cylinder 4 and collected alternately by the pins 17 and 18 on the cylinder 16 until each set of pins has a signature of three sheets. These signatures are folded off onto the 60 folding and delivery cylinder 22 and there slit longitudinally by the slitters 63 into four signatures of twelve pages each and then deposited onto the delivery 24.

Where two sixteen page signatures are to be 65 delivered to the delivery 24 and two eight page signatures to the delivery 23, the web is slit longitudinally into two narrow webs two pages wide and superimposed before passing between the rotary cutter 3 and the cutting and folding 70 cylinder 4. The cams 33 and 62 are operated so that the first and third groups of sheets are taken by the pins 17 on the collecting and folding cylinder 16 and the second group of sheets are folded off onto the cylinder 15; the four 75

superimposed sheets on the cylinder 16 are folded off onto the folding and delivery cylinder 22 and there slit longitudinally by the slitters 63 into two sixteen page signatures and then deposited onto the delivery 24. The second group of sheets which was folded off from the cylinder 4 is slit longitudinally by the slitters 64 into two eight page signatures and then deposited onto the delivery 23.

10 Where two twenty-four page signatures are to be delivered to the delivery 24, the web is slit longitudinally into two narrow webs two pages wide and superimposed before passing them between the rotary cutter 3 and cutting and folding cylinder 4. These groups of sheets are then taken alternately by the pins 17 and 18 on the collecting and folding cylinder 16 until three collections are made on each set of pins. The sheets are then successively folded off onto the folding and delivery cylinder 22 and slit longitudinally by the slitters 63 into two twenty-four page signatures and then deposited onto the delivery 24.

Where one thirty-two page signature is to be delivered to the delivery 24 and one sixteen page signature to the delivery 23, the web is slit longitudinally into four narrow webs one page wide and superimposed before being passed between the rotary cutter 3 and the cutting and folding cylinder 4. The first and third groups of sheets are collected by the pins 17 on the cylinder 16 and the second group of sheets is folded off onto the folding and delivery cylinder 15. The groups of sheets on the cylinder 16 are folded off to their folding and delivery cylinder 22. The signatures on these two cylinders 15 and 22 are then delivered to their respective deliveries 23 and 24.

Where one forty-eight page signature is to be delivered to the delivery 24 the web is slit longitudinally into four narrow webs one page wide and superimposed before being passed between the rotary cutter 3 and the cutting and folding cylinder 4. These groups of sheets are taken alternately by the pins 17 and 18 on the cylinder 16 until three collections are made on each set of pins. These groups of sheets are then successively folded off onto the folding and delivery cylinder 22 and deposited thereby onto the delivery 24.

50 It will be understood that the several cams hereinbefore described are interchanged and operate to produce the various results set forth.

It is evident that various changes may be resorted to in the construction, form and arrangement of the several parts without departing from the spirit and scope of my invention, and hence I do not intend to be limited to the particular embodiment herein shown and described, but

60 What I claim is:

1. Means for cutting the web product of one cycle of a printing press into an odd number of sheets or groups of sheets and means for collecting and folding the sheets or groups of sheets into various paged signatures and delivering them to one or two delivery points, said means including a rotary cutter having an even number of equally spaced cutting blades, and a cutting and folding cylinder having an odd number of cutting slots for successive coaction with said cutting blades, an odd number of equally spaced sheet receiving surfaces and a single folding blade, a coacting collecting and folding cylinder having an even number of equally spaced sheet

5 collecting surfaces and an even number of intermediate equally spaced folding blades, and two folding and delivery cylinders, one having a single folding jaw arranged to coact with the folding blade on the cutting and folding cylinder and the other having a single folding jaw arranged to coact with the folding blades on the collecting and folding cylinder.

2. Means for cutting the web product of one cycle of a printing press into an odd number of sheets or groups of sheets and means for collecting and folding the sheets or groups of sheets into various paged signatures and delivering them to one or two delivery points, said means including a rotary cutter having an even number of equally spaced cutting blades, and a cutting and folding cylinder having an odd number of cutting slots for successive coaction with said cutting blades, an odd number of equally spaced sheet receiving surfaces and a single folding blade, a coacting collecting and folding cylinder having an even number of equally spaced sheet collecting surfaces and an even number of intermediate equally spaced folding blades, and two folding and delivery cylinders, one having a single folding jaw arranged to coact with the folding blade on the cutting and folding cylinder and the other having a single folding jaw arranged to coact with the folding blades on the collecting and folding cylinder, the cutting and folding cylinder and the two folding and delivery cylinders each having the same circumferential length, and the rotary cutter and the collecting and folding cylinder each having two-thirds the circumferential length of the cutting and folding cylinder and the two folding and delivery cylinders.

3. Means for cutting the web product of one cycle of a printing press into three sheets or groups of sheets, means for collecting and folding the sheets or groups of sheets into various paged signatures and delivering them to one or two delivery points, said means including a rotary cutter having two equally spaced cutting blades, a cutting and folding cylinder having three equally spaced cutting slots for successive coaction with said cutting blades, three equally spaced sheet receiving surfaces and a single folding blade, a coacting collecting and folding cylinder having two equally spaced sheet collecting surfaces and two intermediate equally spaced folding blades, and two folding and delivery cylinders, one having a single folding jaw arranged to coact with the folding blade on the cutting and folding cylinder and the other having a single folding jaw arranged to coact with the folding blades on the collecting and folding cylinder.

4. Means for cutting the web product of one cycle of a printing press into three sheets or groups of sheets, means for collecting and folding the sheets or groups of sheets into various paged signatures and delivering them to one or two delivery points, said means including a rotary cutter having two equally spaced cutting blades, a cutting and folding cylinder having three equally spaced cutting slots for successive coaction with said cutting blades, three equally spaced sheet receiving surfaces and a single folding blade, a coacting collecting and folding cylinder having two equally spaced sheet collecting surfaces and two intermediate equally spaced folding blades, and two folding and delivery cylinders, one having a single folding jaw arranged to coact with the folding blade on the cutting

and folding cylinder and the other having a single folding jaw arranged to coact with the folding blades on the collecting and folding cylinder, the cutting and folding cylinder and the two folding and delivery cylinders each having the same circumferential length as the printing cylinder of the press, and the rotary cutter and the collecting and folding cylinder each having two-thirds the circumferential length of the said printing cylinder.

5. In a sheet collecting and folding mecha-

nism for web printing presses, two sheet delivery points, a cutting and folding cylinder, a rotary cutter, a sheet collecting and folding cylinder and two sheet folding and delivery cylinders, the rotary cutter, the collecting and folding cylinder and one of the folding and delivery cylinders each being arranged to coact with the cutting and folding cylinder, and the other folding and delivery cylinder being arranged to coact with the collecting and folding cylinder.

5

HOWARD M. BARBER.
